Dec. 15, 1936.

D. ASHKENAS

2,064,333

POCKETBOOK

Filed July 13, 1935

INVENTOR

Dario Ashkenas
BY
Daniel F. Leon,
ATTORNEY

UNITED STATES PATENT OFFICE

2,064,333

POCKETBOOK

David Ashkenas, Middletown, N. Y.

Application July 13, 1935, Serial No. 31,262

1 Claim. (Cl. 150—33)

This invention relates to a device for attaching articles of apparel such as gloves, handkerchiefs, and the like to women's pocketbooks.

It has been the practice in the past for women to carry gloves in the interior of pocketbooks, but this practice has been attended by distinct disadvantages, especially as far as gloves are concerned. It necessitates the opening of the pocketbook in order to retrieve the gloves, and of course, with each opening the other contents of the pocketbook are exposed and liable to loss. Moreover, because of the small amount of space within a pocketbook and the enormous amount of material carried in the pocketbook by the ordinary woman, the gloves are subjected to a crushing action so that if they are of a frail nature, they will either be soiled or crumpled.

The present invention seeks to relieve these difficulties.

20 The drawing represents a perspective view of an embodiment of my invention.

In the drawing I have shown a pocketbook 1, which is provided with a handle 2, which is permanently stitched or otherwise secured to the 25 pocketbook at its ends.

An extension 3' of the handle 2 is bent back on the handle and is attached to the handle by means of a separable fastener 4'. The distance between the point of permanent attachment of the extension of the handle and the separable fastener is less than the length of the extension, which results in the provision of a loop or keeper, beneath which the articles of apparel may be located and secured.

It will be seen that with this construction the articles of apparel such as gloves, may securely be held in place and available to the user.

What I claim is:—

In a pocketbook, the combination with the back of the pocketbook, of a handle permanently secured thereto at both of its ends, an extension of said handle folded back onto the handle on the side remote from the back of the pocketbook to form a loop or keeper and having a separable fastener adapted to attach its free end to said handle, the distance between the separable fastener and the adjacent point of attachment of the handle to the back of the pocketbook being less than the length of the extension, whereby said loop or keeper is formed.

DAVID ASHKENAS.